UNITED STATES PATENT OFFICE.

JAMES BRAMMER, OF ST. LOUIS, MISSOURI.

SUPPORT FOR PISTONS.

No. 820,695.

Specification of Letters Patent.

Patented May 15, 1906.

Application filed June 26, 1905. Serial No. 267,073.

To all whom it may concern:

Be it known that I, JAMES BRAMMER, a citizen of the United States, and a resident of St. Louis, Missouri, have invented certain new and useful Improvements in Guides and Supports for Pistons and Piston-Valves, of which the following is a specification containing a full, clear, and exact description, reference being had to the accompanying drawings, forming a part hereof.

The various objects of my invention are as follows: first, to lighten the working parts of engines and pumps; second, to do away with packing and packing-glands, vibration-cups, junk-rings, springs on engines or valves which have extension piston-rods and, consequently, third, to dispense with all leaks in the front cylinder-head.

My invention may be applied to piston-valves as well as to pistons of engines or pumps.

In the drawings, Figure 1 is a sectional side elevation of a cylinder and piston having my invention applied thereto. Fig. 2 is a section on line 2 2 of Fig. 1.

1 indicates the usual cylinder for containing the piston or piston-valve 2 and having at one end a common stuffing-box 3. The piston 2 is securely fixed to one end of the piston-rod 4 by any of the ordinary fastening devices. The said piston-rod 4 is provided with an axial bore 5, which opens upon the interior of the cylinder and within which is mounted a supporting-bar 6. Said supporting-bar 6 projects within the cylinder, and its outer end 7 is preferably squared or otherwise arranged to be engaged by a common wrench. A screw-threaded conical enlargement 8 is formed on said supporting-bar at a point near its outer end, and said tapered enlargement is mounted within a threaded seat formed in the cylinder-head 9. Formed in the periphery of said supporting-bar 6 are a series of grooves 10, which extend longitudinally thereof from the conical enlargement 8 to the inner end of the said bar.

The operation is as follows: As the piston or piston-valve reciprocates within the cylinder its weight will be supported by the supporting-bar 6, and all wear of the cylinder due to the weight of the piston or piston-valve will be prevented.

The device is self-lubricating, as it will be lubricated by the lubricant which is sent into the cylinder for the purpose of lubricating the piston or piston-valve.

The outer end of the supporting-bar is made square or angular in order that said bar may be quickly removed after becoming worn and a new one substituted therefor. 60 The supporting-bars can be made in large quantities of standard size, especially for use upon locomotives, in order to interchangeably fit all cylinder-heads. Said supporting-bars may, of course, be made to fit all the different 65 sizes of pistons.

The grooves 10 permit the steam or other fluid to escape from the bore 5 during operation, and thereby permit the piston-rod to work freely upon the supporting-bar. 70

I do not limit myself to the exact construction herein shown, as modifications may be made by skilled mechanics without departing from the scope of my invention.

What I claim is—

1. The herein-described guide and support for pistons and piston-valves, comprising a supporting-bar fixed at one end to the cylinder-head and its opposite end projecting free; said supporting-bar having a venting-groove 80 and extending within a hollow piston and piston-rod. 75

2. The herein-described guide and support for pistons and piston-valves, comprising a supporting-bar fixed at one end to the cylinder-head and projecting within the cylinder, 85 in combination with a piston and piston-rod, said supporting-bar having a screw-threaded conical enlargement near its outer end.

3. The herein-described guide and support for pistons and piston-valves, comprising a supporting-bar fixed at one end to the cylinder-head and projecting within the cylinder, in combination with a piston and piston-rod, said supporting-bar having a screw-threaded 95 conical enlargement near its outer end; said piston-rod having an axial bore within which said supporting-bar extends, the said parts being also provided with suitable venting means for permitting the said supporting-bar 100 to pass freely within the bore of the piston-rod.

In testimony whereof I have signed my name to this specification in presence of two subscribing witnesses.

JAMES BRAMMER.
